ELECTROMAGNETIC SWITCHING DEVICE

DESCRIPTION OF THE INVENTION

The invention relates to a switching device. More particularly, the invention relates to an electromagnetic switching device having a housing comprising two housing parts for accommodating contact and terminal parts and a magnetic system.

In a switching device of the aforescribed type, as disclosed in German Published Document DAS No. 1,246,856, the contact parts, the contact slides and the contact bridges are embedded in the housing part and, after the assembly of the switching device, such components are supported in form-locking relation or are guided in the housing parts. The magnetic system may also be inserted in the housing parts in the known device. The fixed contact parts with the terminal contacts of the support are inserted, at least partly, from outside the housing into slots of the housing parts and are held in the walls of the housing by downwardly bent flaps. In this known switching device, the terminal contacts are free outside the housing and the fastening arrangement utilizing bent flaps is relatively expensive.

An object of the invention is to provide a switching device having a specific separation between the parts rated according to the electrical function and the parts which must be adjusted in accordance with optical and mechanical requirements.

An object of the invention is to provide a switching device which overcomes the disadvantages of known similar types of switching device.

An object of the invention is to provide a switching device of simple structure which functions with efficiency, effectiveness and reliability.

An object of the invention is to provide a switching device having a switching chamber utilizing a material having good qualities with respect to its electrical function but which is generally not utilized because of its mechanical characteristics.

Another object of the invention is to provide a switching device in which the individual components may be installed with facility, rapidity and simplicity, due to a switching chamber which is readily accessible from all sides.

Another object of the invention is to provide a switching device having open clamps in which the clamping screws are prevented from being lost in transit.

Another object of the invention is to provide a switching device which prevents tightening of the clamping screws due to jarring during transit.

Another object of the invention is to provide a switching device wherein the MP conductor for the winding connection may be inserted through an additional terminal screw.

Still another object of the invention is to provide a switching device which permits facile removal of the winding and facile opening of the housing parts without damage to the terminal wires.

In accordance with the invention, the aforescribed specific separation between the electrically rated parts and the mechanically rated parts is provided by a separate switching chamber formed in the housing.

In accordance with the invention, an electromagnetic switching device having a housing comprising two housing parts for accommodating contact and terminal

parts and a magnetic system comprises a separate switching chamber formed in the housing.

The separate switching chamber has outer wall portions integrally formed with the housing parts to provide form-locking support for frame clamps.

A frame having internally threaded bores formed therein in frame clamps are provided. Each of the frame clamps has a terminal clamping screw having a head and an externally threaded conical end threadedly engaging a corresponding one of the bores. The separate switching chamber is spaced from the housing parts by a length distance corresponding to the height of a frame clamp plus the length of the terminal clamping screw less the conical end of the terminal clamping screw to accommodate the frame clamps. The housing has openings formed therethrough each located over the head of a corresponding one of the terminal clamping screws and each of a cross-sectional area smaller than the cross-sectional area of a terminal clamping screw. The head of each of the terminal clamping screws has a recess formed therein to accommodate a test plug.

Winding leads extend between the separate switching chamber and the housing parts. The magnetic system has a winding connected at each end to a winding lead.

Each of the housing parts has a projection formed therein on the inside of the housing and each of the winding leads is of bar-shape having an opening formed therein in engagement with a corresponding one of the projections.

A winding lead has a bent end extending through the housing to outside the device. An additional terminal clamping screw is affixed to the bent end of the winding lead.

The winding has ends, and contact springs are in electrical connection at one end with a corresponding end of the winding and in electrical connection at the other end with a corresponding winding lead. Each of the contact springs is in force-locking connection between a corresponding end of the winding and a corresponding winding lead.

The switching device of the invention permits the separate switching chamber to comprise high quality material having good qualities with respect to its electrical function, but which could not be utilized for the mechanical factors required for the housing. The optical qualities need not be considered when selecting the material for the switching chamber, since said switching chamber is covered. Since the separate switching chamber is readily accessible from all sides, and also transversely to the closing direction of both housing parts, the individual components may be installed in the switching device with simplicity, rapidity and facility. All the openings required for mounting the switching device are closed by the housing parts after their assembly.

The frame clamps are supported in form-locking arrangement in a particularly simple manner when the outer wall portions of the separate switching chamber are integrally formed with the housing parts. The arrangement of the clamping screws permits the switching device to be delivered with open clamps while preventing the loss of said screws in transit. The clamping screws are also prevented from tightening during jarring of the switching device in transit, since a clamping screw would have to lift the frame in order to accomplish this. The head of each clamping screw is provided

with a recess formed therein to accommodate a test plug, since the terminal parts are almost completely covered.

The extending of the winding lead for the winding of the magnetic system between the separate switching chamber and the housing parts permits the insertion of the terminal clamping screws in the same height or level. The tight bearing of the housing parts against the separate switching chamber permits projections formed inside the housing to engage openings formed in the bar-shaped winding leads, thereby permitting a bent end of a winding lead to be guided through the wall of a housing part and to be provided with an additional terminal clamping screw. This permits the MP conductor for the winding connection to be pushed or pulled through at the additional terminal clamping screw. The provision of a contact spring for the winding of the magnetic system in force-locking contact with the winding lead when a housing part is in an assembled condition, permits the removal and exchange of the winding with rapidity, facility and simplicity without damage to the terminal wires.

In order that the invention may be readily carried into effect, it will now be described with reference to the accompanying drawings, wherein:

FIG. 1 is a lateral section through a contact path of an embodiment of the switching device of the invention;

FIG. 2 is a lateral section through the center of the embodiment of the switching device of FIG. 1, in which the winding connections are shown; and

FIG. 3 is a cross-sectional view of the embodiment of the switching device of FIG. 1.

In the FIGS., the same components are identified by the same reference numerals.

The electromagnetic switching device of the invention, as shown in the FIGS., comprises two housing parts 1 and 2. The housing parts 1 and 2 form the housing of the switching device which housing accommodates a magnetic system comprising a stationary magnetic component 3, a movable magnetic component 4 and a winding 5, as shown in FIG. 1. The housing part 1 has two projections 6a and 6b formed on the inside thereof and the housing parts 2 has two projections 6'a and 6'b formed on the inside thereof. The projections 6a, 6b, 6'a and 6'b support the winding 5.

The movable magnetic component 4 is connected to a contact bridge carrier 7 which supports contact bridges 8. The contact bridges 8 cooperate with fixed contacts 9 and 9'. Contact pressure springs 10 provide contact pressure and are located in the contact bridge carrier 7. The fixed contact parts 9 and 9' are connected to electrical conductors from outside the switching device via frame clamps 11. The frame clamps 11 accommodate the free ends 12 and 12' of the fixed contact parts 9 and 9', respectively.

Each frame clamp 11 has a terminal clamping screw 13. The frame clamps 11 are separated from the actual switching chambers which enclose the contact bridges 8 and the fixed contact parts 9 and 9'. The separation of the frame clamp 11 from the switching chambers is provided, in accordance with the present invention, by a separate switching chamber 14. The separate switching chamber 14 may also be utilized to support and guide frame clamps 11. In order to accomplish this, the separate switching chamber 14 is provided with outer wall portions 15 and 16 integrally formed with the

housing part 1 and outer wall portions 15' and 16' integrally formed with the housing part 2. The frame 20 of each frame clamp 11 is guided on the outer wall portions 15 and 16 when the terminal clamping screw 13 is loosened, or turned so that it moves upward.

Each of the housing parts 1 and 2 has an opening 17 formed therethrough over the head of each terminal clamping screw 13. Each of the openings 17 has a cross-sectional area smaller than the cross-sectional area of a terminal clamping screw 13. The opening 17 is to permit the introduction of a screw driver to turn the terminal clamping screw 13 in either direction.

Each terminal clamping screw 13 has a conical end 18 adjacent the opening in the frame 20. The terminal clamping screws 13 are maintained in the housing without loss. The movability of each terminal clamping screw transverse to its longitudinal axis is so limited by the separate switching chamber 14 and the corresponding housing part 1 or 2 that the terminal clamping screws are prevented from slipping out of the housing via corresponding openings 19 formed in the frame 20 at their conical ends 18.

During the assembly of the switching device of the invention, the need for turning the terminal clamping screw 13 is eliminated, thereby permitting a simplification in mounting. Furthermore, the terminal clamping screws 13 are prevented from loosening when the switching device is connected to its mounting. The conical end 18 of each terminal clamping screw 13 is externally threaded and threadedly engages internal threading provided in each of the openings 19 when the screw is turned in the proper direction. It is therefore only necessary, at the place of mounting, to insert outside insulated conductors into corresponding ones of insertion funnels 21, a plurality of which are provided in the housing parts 1 and 2. When an outside electric conductor is inserted into a corresponding insertion funnel 21, the corresponding frame 20 is lifted due to the pulling up of the corresponding terminal clamping screw 13, as shown on the left-hand side of FIG. 1.

Each of the terminal clamping screws 13 has a recess 22 formed in its head, as shown in FIG. 1, to accommodate a test plug. On one hand, the ends 12 of the fixed contact part 9 brace against inwardly extending projections 23 formed in the housing parts 1 and 2. On the other hand, as shown in FIG. 3, the ends 12 of the fixed contact part 9 abut the separate switching chamber 14 in grooves, recesses, or the like, 24 formed in said separate switching chamber, thereby providing a force-locking support.

FIG. 2 shows winding leads 25 and 25' extending between the separate switching chamber 14 and the housing parts 1 and 2, respectively. Each winding lead 25 and 25' comprises a bar-shaped electrical conductor having an opening 25a and 25'a, respectively, formed therein. Inwardly extending projections 26 and 26' of the housing parts 1 and 2, respectively, are in engagement with corresponding openings 25a and 25'a of the winding leads 25 and 25'. This permits the shifting of the winding leads 25 and 25'. The winding lead 25' has a bent end 27 which extends out through the wall of the housing part 2. The bent end 27 of the winding lead 25' is provided with a threaded boss 28 having an additional terminal clamping screw 29 in threaded engagement therein. The additional terminal clamping screw 29 permits the insertion of an outside PM conductor for connecting the magnetic winding 5.

The electrical connections between the ends of the winding 5 and the corresponding winding leads 25 and 25' are provided by springs 30 and 30', respectively. The springs 30 and 30' are of leaf type, and pass through electrically insulating material 30a and 30'a, respectively, on the outside of the winding 5. Each of the springs 30 and 30' is in electrical connection at one end with an end of the winding 5 and in electrical connection at the other end with the corresponding winding lead 25 or 25'.

When the switching device of the invention is mounted, the bridge contact carrier 7 is first led through a guide opening 31 in the separate switching chamber 14 and is connected to the movable magnetic component 4. The fixed contact parts 9 and 9' are affixed in a simple manner, either before or after the positioning of the bridge contact member, depending upon whether a closing or opening contact is present. The fixed contact parts 9 and 9' are merely inserted into corresponding ones of grooves 32 formed in the separate switching chamber 14. The ends 12 and 12' of the fixed contact parts 9 and 9', respectively, which co-operate with the projections 23 and 23' formed in the housing parts 1 and 2, respectively, prevent said fixed contact parts from sliding back.

The frames 20 are guided across the ends 12 and 12' of the fixed contact parts 9 and 9', respectively (FIG. 1), or bent parts 33 and 33' of the winding leads 25 and 25', respectively, engage said frames and are moved so that openings formed in said bent parts engage projections 26a and 26'a, respectively, of the housing parts 1 and 2. The terminal clamping screws 13 are then provided. Thus, after the stationary magnetic component 3 and the winding 5 are inserted, the housing parts 1 and 2 may be closed on each other.

The electromagnetic switching device is thus of very simple structure and is completely free from impairment in function due to such simplicity of structure. On order to enhance the stability of the separate switching chamber 14 and the housing parts 1 and 2, gears 34 may be provided at said separate switching chamber, as shown in FIG. 3. The gears 34 engage the housing parts 1 and 2 in force-locking relation.

While the invention has been described by means of a specific example and in a specific embodiment, we do not wish to be limited thereto, for obvious modifica-

tions will occur to those skilled in the art without departing from the spirit and scope of the invention.

We claim:

1. An electromagnetic switching device of the type having contact and terminal parts and a magnetic system, comprising a housing having two housing halves, means integrally formed on said housing defining a separate switch chamber within said housing, frame clamp means disposed in said chamber for receiving and 10 clamping electrical conductors, said chamber defining means having support means for mounting and movably supporting said frame clamp means within said chamber to provide for said frame clamp means effecting a clamping action with said electrical conductors, 15 said frame clamp means comprising frame clamps having internally threaded bores formed therein, each of the frame clamps having a terminal clamping screw disposed within said chamber and having a head and an externally threaded conical and threaded engaging a 20 corresponding one of said bores, said chamber defining means comprising internal wall means spaced from an opposite end wall of said housing by a length distance corresponding to the height of a frame clamp plus the length of the terminal clamping screw less the conical 25 end of the terminal clamping screw, said housing having openings formed therethrough each located over the head of a corresponding one of the terminal clamping screws and each of a cross-sectional area smaller than the cross-sectional area of a terminal clamping screw.
2. An electromagnetic switching device as claimed in claim 1, wherein the head of each of the terminal clamping screws has a recess formed therein to accommodate a test plug.
3. An electromagnetic switching device as claimed in claim 1, wherein said two housing halves each has a portion defining one-half of said chamber, said terminal clamping screws being received in said bores of said 40 frame clamps before said housing halves are assembled whereby after assembly, said terminal screws are not removable from their respective bores so that said device may be initially provided with open frame clamps while preventing the loss of said terminal screws in transit.
